CLAIM

The ornamental design for an oral care implement, as shown and described.

DESCRIPTION

FIG. 1 is a front perspective view of an oral care implement according to a first embodiment of the new design;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is an enlarged top view thereof;
FIG. 8 is an enlarged bottom view thereof;
FIG. 9 is a front perspective view of an oral care implement according to a second embodiment of the new design;
FIG. 10 is a rear perspective view thereof;
FIG. 11 is a front view thereof;
FIG. 12 is a rear view thereof;
FIG. 13 is a left side view thereof;
FIG. 14 is a right side view thereof;
FIG. 15 is an enlarged top view thereof; and,
FIG. 16 is an enlarged bottom view thereof.

The broken lines illustrate portions of the oral care implement that form no part of the claimed design.

1 Claim, 10 Drawing Sheets
